TRANSFORMER TANK STRUCTURE

William G. James, West Middlesex, Pa., assignor
to Westinghouse Electric & Manufacturing
Company, East Pittsburgh, Pa., a corporation
of Pennsylvania

Application May 17, 1935, Serial No. 21,986

1 Claim. (Cl. 285—111)

This invention relates to transformer cases and particularly to sectionalized transformer cases in which it is desired to have an oil or gas-tight joint between the different sections of the case.

5 An object of this invention is the provision of a simple and efficient joint construction which is adapted to provide leak proof joints in cases for electrical apparatus.

This invention, together with additional objects and advantages thereof, will be better understood from the following description when taken in conjunction with the accompanying drawing, in which

15 Figure 1 is a view partly in elevation and partly in section, showing an oil immersed transformer in a sectionalized case, the joints of which embody the features of this invention, and

20 Fig. 2 is an enlarged vertical sectional view showing the joint between the upper and lower sections of the sectionalized case.

Like reference characters indicate similar parts in the different figures of the drawing.

Referring to the drawing and particularly to Fig. 1, a sectionalized transformer case 10 comprising an upper case section 11 and a lower case section 12 is shown. A cover 13 is provided for the upper case section 11 and is maintained thereon by suitable means such as bolts 9.

The case 10 contains oil 14 or other suitable 30 insulating medium in which the transformer core 15 is immersed. As is usual in oil immersed transformers, the case 10 is large enough to contain the oil necessary for the cooling of transformer core 15, the transformer leads 16 and the 35 bushings 17.

As illustrated in Fig. 1 and shown in the enlarged vertical sectional view in Fig. 2, a ring flange or stop 18 is provided at a point above the transformer core 15 around the inner wall 40 of the lower case section 12 in order to provide a rest or stop for supporting the upper case section 11 in its position relative to the lower section 12. The ring flange 18 is securely welded, as at 19, to the lower section 12 to provide a mechanically strong stop for carrying the weight 45 of upper section 11 and to support it in assembled position.

A ring flange 20 is provided around the inner wall of the upper section 11 at its lower edge to 50 cooperate with the flange 18 in positioning the upper section 11 in assembled relation with the lower section 12. The ring flange 20 is securely welded to the upper section 11 by welds 21.

A plurality of openings 22 are provided in the 55 ring flanges 18 and 20 for receiving the cap

screws 23 for mechanically holding the upper and lower sections in assembled relation. The cap screws 23 are so spaced around the ring flanges as to withstand the mechanical stresses encountered in moving or lifting the case. The 5 gasket 24 is provided between the ring flanges 18 and 20 for shop testing purposes and oil and gas tight shipment.

In order to assist in positioning the upper section 11 and to prevent the crushing of gasket 24, 10 a bead stop 25 is provided on the ring flange 18.

As is evident from the drawing, the upper and lower sections are assembled in telescopic relation with the upper section 11 being of smaller diameter than the lower section 12 and fitting 15 therein and being supported by the ring flange 18 of the lower section. When the sections are thus assembled, the upper end of the lower section 12 extends upwardly to a point above the joint formed by the flanges 18 and 20. In this 20 particular embodiment, the sections 11 and 12 are loosely fitted together in telescopic relation. When thus assembled the upper edge of the lower section 12 is forced into contact with the upper section 11 and is secured thereto by a weld 26. 25 As will be understood, the case sections 11 and 12 may be of such a size that when assembled they will be in close contact with each other. When thus assembled, it is not necessary to deform the upper edge of the lower section. The 30 weld 26 unites the lower section and the upper section and provides a leak proof joint therebetween.

In order to test the joints between the upper and lower sections, a pipe plug 27 is provided at 35 some convenient point between the ring flange 18 and the upper edge of the lower section 12. As will be evident to those skilled in the art, the pipe plug 27 may be removed after the case is assembled and the joints are welded so that compressed air or some other suitable medium can be applied to test the joints for leaks. If a leak 40 is discovered, it can be easily stopped by welding at the point of the leak. After the pressure testing is completed, the pipe plug 27 is replaced in 45 the opening providing a closed and leak proof sectionalized case.

From the foregoing description, it is evident that this invention provides a sectionalized case which is adapted to be shipped in dismantled 50 form with the transformer in the lower case section and which is adapted to be easily assembled in the field. Further, it is evident that this invention provides a simple and efficient joint between the assembled sections so that when cor- 55

rectly assembled and welded, as hereinbefore set forth, a leak proof case results.

It is, of course, to be understood that although this invention has been shown and described with reference to certain specific embodiments thereof, many modifications are possible, and it is, therefore, not to be restricted except insofar as is necessitated by the prior art and the scope of the appended claim.

10 I claim as my invention:

A joint structure for use in a vertically extending sectionalized case having a lower section of major diameter and an upper section of minor diameter comprising, means disposed around the lower section and below its upper edge for supporting the upper section in telescopic relation,

said means comprising a horizontal flange projecting inwardly from the internal surface of the lower section, means comprising another inwardly extending horizontal flange disposed around the upper section at its lower edge to cooperate with the flange of the lower section in positioning the sections in assembled relation, the lower section extending upwardly beyond and external of the lower edge of the upper section, the upper edge of the lower section of major diameter being forced into contact with the external surface of upper section of minor diameter, and a weld for uniting the contacting upper edge of the lower section to the external surface of the upper section to provide a leakproof joint therebetween. 10 15

WILLIAM G. JAMES.
